United States Patent Office

Des. 201,789
Patented Aug. 3, 1965

201,789

TOOTHBRUSH HOLDER OR SIMILAR ARTICLE

Eli M. Milakovich, 14311 E. 4th St., Whittier, Calif.

Filed Sept. 21, 1964, Ser. No. 81,819

Term of patent 14 years

(Cl. D4—3)

FIG. 1.

FIG. 2.

FIG. 3.

FIG. 4.

FIG. 5.

FIG. 6.

FIG. 1 is a perspective view of a toothbrush holder showing my new design;

FIG. 2 is a front elevational view thereof;

FIG. 3 is a side elevational view thereof;

FIG. 4 is a rear elevational view thereof;

FIG. 5 is a top plan view thereof; and

FIG. 6 is a bottom plan view thereof.

The side of the toothbrush holder which is not shown has substantially the same appearance as the side which is shown in FIG. 3, described above.

I claim:

The ornamental design for a toothbrush holder or similar article, substantially as shown and described.
